INVENTOR.
WILLIAM E. MENOLD
BY *Victor J. Evans*
ATTORNEY.

UNITED STATES PATENT OFFICE.

WILLIAM E. MENOLD, OF SPOKANE, WASHINGTON.

CLOTHESLINE-TERMINAL GRIP.

Application filed October 27, 1923. Serial No. 671,211.

To all whom it may concern:

Be it known that I, WILLIAM E. MENOLD, a citizen of the United States, residing at Spokane, in the county of Spokane and 5 State of Washington, have invented new and useful Improvements in Clothesline-Terminal Grips, of which the following is a specification.

This invention relates to improvements in 10 clothes-line terminal grips.

The principal object of this invention is to provide means for engaging and holding the end of a clothes-line against accidental withdrawal.

15 A still further object is to produce a device of this character which is extremely simple in construction and therefore cheap to manufacture.

Another object is to provide means where- 20 by the rope being held may be quickly released.

Other objects and advantages will be ap- 25 parent during the course of the following description.

25 In the accompanying drawings forming a part of this specification, and in which like numerals are employed to designate like parts throughout the same,

Figure 1 is a side elevation of my device, 30 Figure 2 is a front elevation of my device, and

Figure 3 is a vertical cross section, showing the manner of operating my device.

Applicant is aware that many forms of 35 clothes-line gripping devices have been placed upon the market. Most of these devices, however, have necessitated the tying of a knot in a rope or have entailed a complicated clamping mechanism.

40 I have therefore sought to provide a clothes-line grip which may be operated by one hand, if necessary, and one which will not require the tying of knots or will not mutilate the rope.

45 In the accompanying drawings wherein for the purpose of illustration is shown a preferred embodiment of my invention, the numeral 5 designates a plate having open- 100 ings 6 and 7 formed therein, for the pur- pose of fastening my device to a suitable support, such as a clothes-pole, building or the like.

At 8 and 9 are shown wings preferably bent at right angles to the plate 5. These wings serve to pivot a U-shaped member 11 55 pivoted upon a pin 12 extending through the wings 8 and 9. This U-shaped member carries a pin 13 upon which is mounted a pulley 14.

It will be noted by viewing Figures 1 and 60 2 that the pivotal pin 12 is mounted below the center of the U-shaped member 11. The reason for this is that when a line, as shown at A, is passed over the pulley 14 and the end brought down between the plate 5 and 65 the portion 16 of the U-shaped member, the pull of the rope against the pulley 14 will be great enough to cause the portion 16 to tightly engage or clamp the rope against the plate 5, the result being that a person may 70 use one hand to pull downwardly upon the ends of the rope and immediately upon letting go a clamping action will take place.

When it is desired to release the rope, it is merely necessary to push upon the up- 75 ward end of the U-shaped member or pulley 14 which will disengage the portion 16 from its contact with the rope.

It will thus be seen that I have provided a very simple device and one which is very 80 efficient in operation.

It is to be understood that the form of my invention herewith shown and described is to be taken as a preferred example of the same and that various changes in the shape, 85 size and arrangement of parts may be resorted to without departing from the spirit of the invention or the scope of the subjoined claim.

Having thus described my invention, I 90 claim:—

In a gripping device, a plate, wings formed at right angles to said plate, a U-shaped member pivoted between said wings, the pivotal point of said U-shaped member 95 being nearer one end of said U-shaped member than the other in such a manner that the edge of the U-shaped member will contact a rope positioned between said U-shaped member and said plate, and a pulley pivoted 100 to the remote end of said U-shaped member.

In testimony whereof I affix my signature.

WILLIAM E. MENOLD.
